(57) **CLAIM**

The ornamental design for a display case with curved front, as shown and described.

DESCRIPTION

FIG. 1 is a perspective view of the display case with curved front according to the present application.

FIG. 2 is a front view of the display case with curved front according to the present application.

FIG. 3 is a right side view of the display case with curved front according to the present application. The left side view is a mirror image of the right side view.

FIG. 4 is a top view of the display case with curved front according to the present application. The bottom view is a mirror image of the top view.

FIG. 5 is a perspective view of a first alternative embodiment of the display case with curved front according to the present application.

FIG. 6 is a front view of the display case with curved front of FIG. 5 according to the present application.

FIG. 7 is a right side view of the display case with curved front of FIG. 5 according to the present application. The left side view is a mirror image of the right side view; and,

FIG. 8 is a top view of the display case with curved front of FIG. 5 according to the present application. The bottom view is a mirror image of the top view.

The broken lines in all views are for illustrative purposes only and form no part of the claimed design.
